Ralph A. Corley, Mountain Lakes, N. J.

Application June 23, 1942, Serial No. 107,314

Term of patent 14 years

To all whom it may concern:

Be it known that I, Ralph A. Corley, a citizen of the United States of America, residing at 116 Laurel Hill Road, Mountain Lakes, Morris County, State of New Jersey, have invented a new, original, and ornamental Design for a Pipe Coupling, of which the following is a specification, reference being had to the accompanying drawing, forming a part thereof, and wherein:

Fig. 1 is a top plan view of a pipe coupling showing my new design.

Fig. 2 is an end view of the coupling illustrated in Fig. 1.

I claim:

The ornamental design for a pipe coupling, substantially as shown.

RALPH A. CORLEY.
